UNITED STATES PATENT OFFICE.

WALTER V. TURNER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FLUID-COMPRESSOR.

1,176,108.

Specification of Letters Patent. Patented Mar. 21, 1916.

Application filed January 19, 1915. Serial No. 3,051.

To all whom it may concern:

Be it known that I, WALTER V. TURNER, a citizen of the United States, residing at Edgewood, in the county of Allegheny and 5 State of Pennsylvania, have invented new and useful Improvements in Fluid-Compressors, of which the following is a specification.

This invention relates to compound steam 10 pumps, and more particularly to the direct acting type in which the engine pistons are directly connected to the pump or compressor pistons. Some difficulty has heretofore been experienced in cases where excessive leakage occurs from the live steam 15 side of the high pressure steam piston to the exhaust steam side, since this reduces the differential of pressures acting on the high pressure piston and results in a slowing 20 down of the pump.

The principal object of my invention is to provide means for relieving the high pressure steam pistons of back pressure due to the exhaust steam where the same operates to 25 retard the movement of the high pressure piston so that the low pressure piston completes its stroke first.

In the accompanying drawings; Figure 1 is a central vertical section of a compound 30 steam pump embodying my improvement, showing the parts in position when the high pressure steam piston is making its up stroke and the low pressure piston its down stroke and Fig. 2 a similar view, showing 35 the parts in position when the high pressure steam piston is making its down stroke and the low pressure piston its up stroke.

According to the construction shown in the drawings, the high pressure steam piston 40 1 contained in cylinder 2 is connected by rod 3 with low pressure air piston 4 contained in cylinder 5; while the low pressure steam piston 6, contained in cylinder 7 is connected by rod 8 with high pressure air 45 piston 9 contained in cylinder 10.

A steam distribution valve controls the admission and exhaust of steam to and from the steam cylinders and may comprise a series of piston heads 11, 12, 13, and 14 and 50 a differential piston head 15 having a greater area than the other piston heads, the piston head 11 having a lesser area than the intermediate piston heads 12, 13, and 14.

A reversing valve 16 is provided for controlling the movement of the main steam 55

distribution valve and is adapted to be actuated in the usual manner by the movement of the high pressure steam piston to the end of its stroke.

With the steam distribution valve in the 60 position shown in Fig. 1, steam supplied through pipe 25 and passage 17 flows to the space between piston heads 11 and 12 and thence through passage 18 to the chamber below high pressure steam piston 1, thus 65 causing said piston to make its up stroke. When the high pressure piston reaches the end of its stroke, the reversing valve 16 is shifted to its upper position, in which passage 19 is uncovered, so that steam is supplied from valve chamber 20 to the outer 70 face of piston head 15. Since the outer face of piston head 11 is open to the atmosphere through passages 21 and 22 and pipe 23, the unbalanced steam pressure acting on piston 75 head 15 operates to shift the steam distribution valve to the position shown in Fig. 2 of the drawings. Live steam is now supplied to the upper side of piston 1 from the space between piston heads 14 and 15 and 80 through passage 24, so as to cause the high pressure steam piston 1 to move downwardly. Exhaust steam from the chamber at the lower face of piston 1 is also admitted to the chamber below the low pressure steam piston 6 through passage 18, 85 space between piston heads 12 and 13, and passage 26. The space above piston 6 is connected to the exhaust through passage 90 27, space between piston heads 13 and 14, and passage 22 and the low pressure steam piston is therefore moved upwardly by the exhaust steam from the high pressure steam cylinder.

When the high pressure steam piston 95 reaches the end of its down stroke, the reversing valve 16 is shifted to its lower position, in which, as shown in Fig. 1, the chamber at the outer face of piston head 15 is connected to the atmosphere through passage 100 28, cavity 29 in the reversing valve 16, and passages 30, 21, and 22. The unbalanced steam pressure now acting in the space between piston heads 14 and 15 on the differential area of piston head 15 then operates to 105 shift the steam distribution valve to the position shown in Fig. 1, so that live steam is admitted to the lower side of piston 1 through passage 18 while exhaust steam from above the piston 1 is supplied to the 110

upper side of low pressure piston 6 through passage 24, space between the piston heads 13 and 14, and passage 27. The air pistons 9 and 4 are thus operated by the steam pistons 5 tons 6 and 1 to compress air, the low pressure piston 4 taking air from the atmosphere and compressing the same into the high pressure air cylinder in the usual manner.

The operation above described corresponds with that of the compound compressor heretofore employed, but according to my present invention, additional passages 31 and 32, controlled by the steam distribution valve, are provided, the passage 31 10 opening into the low pressure steam cylinder 7 at a point just above the piston 6 when the same is in its lowermost position and the passage 32 opening into the cylinder 7 at a point just below the piston 6 when the same is in its uppermost position.

Referring to Fig. 1 of the drawings, it will be seen that passage 31 is now connected to passage 22 and the atmospheric exhaust, so that when the low pressure piston 25 ton 6 completes its down stroke, the chamber above the piston is opened directly to the exhaust and the exhaust steam above the low pressure piston which has done its work is thus exhausted as well as the exhaust steam 30 remaining above the high pressure steam piston 1. It will thus be seen that in case the movement of the high pressure steam piston is retarded by leakage of steam around the piston or by other causes, the 35 pack pressure of the exhaust steam being relieved, the prompt movement of the high pressure steam piston is facilitated.

When the high pressure steam piston reaches the end of its up stroke, the reversing 40 valve is operated to effect the movement of the steam distribution valve to the position shown in Fig. 2, in which the piston head 13 blanks the port opening of passage 31, so that this passage will be closed against 45 the escape of steam as the low pressure steam piston makes its up stroke.

Referring to Fig. 2 of the drawings, when the low pressure steam piston is making its up stroke, the passage 32 is connected by 50 the space between piston heads 12 and 13 with exhaust passage 22, so that at the end of the up stroke, the under side of the low pressure steam piston is directly connected to the exhaust and the exhaust steam pressure is released from the under side of the 55 low pressure piston side and also from the under side of the high pressure steam piston 1, so that the prompt downward movement of the high pressure steam piston is facilitated.

The movement of the high pressure steam

piston 1 to the end of its down stroke operates the reversing valve 16 so as to effect the movement of the steam distribution valve to the position shown in Fig. 1, in 65 which the piston head 13 blanks the port opening of passage 32, so that escape of steam is prevented as the low pressure steam piston 6 makes its down stroke.

It will now be seen that by means of my 70 invention, the prompt movement of the high pressure steam piston is assured and that this is accomplished without the use of additional mechanism, simply by employing two extra passages. 75

Having now described my invention, what I claim as new and desire to secure by Letters Patent, is:

1. In a compound steam pumping engine, the combination with a high pressure steam 80 piston and cylinder and a low pressure steam piston and cylinder, of a valve mechanism for controlling the admission of steam to said cylinders and a passage controlled by the movement of the low pressure piston 85 and also by said valve mechanism for relieving the low pressure piston of exhaust steam pressure with said valve mechanism in position for supplying steam to the relieved side of the piston. 90

2. In a compound steam pumping engine, the combination with a high pressure steam piston and cylinder and a low pressure steam piston and cylinder, of a valve mechanism for connecting the exhaust steam side 95 of the high pressure piston with one side of the low pressure piston and adapted while in this position to open a passage which is connected to the same side of the low pressure piston by the movement of the 100 low pressure piston to the end of its stroke, for relieving the pistons of exhaust steam pressure.

3. In a compound steam pumping engine, the combination with a high pressure steam 105 piston and cylinder and a low pressure steam piston and cylinder, of a main steam distribution valve for connecting the exhaust steam side of the high pressure piston with one side of the low pressure piston and 110 a passage connected to the exhaust through said valve in the same position and opened to the same side of the low pressure piston upon movement of the low pressure piston to the end of its stroke for venting the 115 exhaust steam from both pistons.

In testimony whereof I have hereunto set my hand.

WALTER V. TURNER.
